UNITED STATES PATENT OFFICE.

BENJAMIN S. GALLUP, OF HAMMOND, LOUISIANA.

CAR-LOAD BRACE.

1,358,724.

Specification of Letters Patent. Patented Nov. 16, 1920.

Application filed October 31, 1919, Serial No. 334,702. Renewed September 29, 1920. Serial No. 413,635.

To all whom it may concern:

Be it known that I, BENJAMIN S. GALLUP, a citizen of the United States, residing at Hammond, in the parish of Tangipahoa and 5 State of Louisiana, have invented certain new and useful Improvements in Car-Load Braces, of which the following is a specification.

This invention relates to car-load braces, 10 and consists of an improved device of the character mentioned which is adapted to efficiently and positively maintain a load of articles in place during transportation, irrespective of the shape and size of the load, 15 or the nature of the articles of which it may consist.

While retaining some features of my earlier form of load-brace, as shown in Patent No. 1,187,898, issued to me on June 20, 20 1916, and on which it is an improvement, the present device is characterized by the use of a single bracing element for the entire load, in the form of a gate, as distinguished from the several individual tier-bracing members 25 made use of in the earlier form of the device above referred to. The number of parts necessary in individual tier-bracing is thus materially reduced, and only such supporting and securing means required as are essential to the proper operation of the gate.

The present invention further comprises improved supporting and take-up means for the upper end of the load-bracing member which, in addition to maintaining the gate 35 in constant binding relation to the load, notwithstanding shifting of the latter during transit, will readily permit the gate when not in use to be swung up against the car ceiling and moved freely together with its 40 supporting and take-up means in either direction length-wise of the car.

It is also desired to provide a device of the character mentioned which is so constructed as to permit of its being readily positioned relative to the load should the same be high and extend close to the middle of the car, the gate being transversely hinged substantially midway of its height for this purpose. Further means are provided for 50 maintaining the gate rigid when so desired.

Another object is to provide novel means for adjustably securing the lower end of the bracing member or gate against the load, use being made for this purpose of a mechanism similar in principle to that of the upper gate securing means.

With the above and other objects in view as will readily appear upon consideration of the following description, taken in conjunction with the accompanying drawings, my 60 invention consists of the parts, and construction and combination of parts, hereinafter more fully described and claimed, reference being had to the drawings, in which:

Figure 1 is a cross-sectional view of a 65 refrigerator car showing the device in front elevation as it appears in operative position with relation to a load of stacked crates;

Fig. 2, a longitudinal sectional view of a 70 portion of a car, the operative positions of the load brace and its attachments with relation to the load of crates being clearly shown;

Fig. 3, an enlarged side elevational view of the upper portion of the gate with its 75 hinged joint, and the automatic take-up device, certain parts thereof being broken away for sake of clearness;

Fig. 4, a sectional view taken on line 4-4 of Fig. 3, which shows clearly the interior 80 construction of the gate hanger and the relation of the other parts of the device thereto;

Fig. 5, a side elevational view of the device with the gate swung up against the car ceiling in the position in which it is kept 85 when not in use, parts of the device being broken away for sake of clearness;

Fig. 6, a sectional view taken on line 6-6 of Fig. 5, showing in front elevation, the means for securing the lower end of the gate 90 in the position shown in Fig. 5;

Fig. 7, a fragmentary front elevational view of the locking means for maintaining the gate rigid at the hinged joint, when so desired;

Fig. 8, an enlarged front elevational view of the means for securing the lower end of the gate;

Fig. 9, a plan view of the same; and

Fig. 10, a sectional view taken on line 100 10-10 of Fig. 9.

Referring to the attached drawings, in which like numerals indicate corresponding parts throughout the several views, the load-bracing gate is shown as consisting of vertical members 1 and cross members 2, forming the gate frame upon the inner face of which is secured a series of slats 3. Vertical members 1 extend above the main gate structure, and are provided at their upper extremities with certain novel supporting and take-up means adapted to connect the gate 105 110

with supporting rails or tracks 4 from which it is suspended. Rails 4 are held in proper position adjacent the car ceiling by means of suitable brackets 5 at each end thereof, said rails being of sufficient length to extend a substantial distance toward the ends of the car on each side of the center thereof.

The supporting and take-up devices above referred to are designed to operate on the same principle as the devices for this purpose described in my patent hereinbefore mentioned. In the present device, each of the rails 4 is provided with a main dog 6 and a take-up or spring dog 7, both of which are slidably and adjustably mounted thereon. Interposed between said dogs, is a spiral spring 8, the same being attached to dog 6 at a point immediately beneath the rail 4 and to spring dog 7 at its lower extremity by means of eye-bolts 9 secured in said dogs. It is necessary that spring 8 be of sufficient strength to force spring dog 7 to maintain a rigid and positive grip upon rod 4 when said spring is under tension, as is the case when the gate is in operative position against the face of the load.

Main dog 6 is connected to the gate by means of a chain section 10, one end of the chain being connected to the lower end of said dog, while the opposite end is attached to eye-bolt 11 secured in the upper end of member 1 of the gate.

A hanger 12, of inverted U-form in cross-section, partially incloses dog 6, said hanger straddling rail 4 on which it is adapted to travel in either direction by means of rollers 13. Dog 6 is adapted to travel back and forth in unison with hanger 12, as will be hereinafter explained. Spreader member 14 serves to maintain the depending sides of hanger 12 in proper position relative to the parts inclosed therein, so as not to interfere with the proper functioning of the latter. Each hanger 12 is further provided with a pin 15 near its lower edge with which hooks 16 on the upper ends of members 1 of the gate are adapted to engage in order to support said gate independent of dogs 6, preliminary to swinging the gate into its horizontal position against the car ceiling when not in use, or for the purpose of moving the gate supporting and take-up means along tracks 4.

Lugs 17 are provided, projecting inwardly from the sides of hanger 12 and so positioned with relation to dog 6 as to cause the latter to slide freely on rail 4 upon the movement of hanger 12 in either direction. While placed sufficiently close to the faces of dog 6 as to cause the latter to move in unison with hanger 12, said lugs are not so close as to interfere with the slight pivotal movement of the dog necessary to its binding action on rail 4, as when the parts of the device are secured in operative posi-

tion relative to the load. Means are also provided to enable dog 7 to be moved along rail 4 with hanger 12 and dog 6 without said dog exercising its binding action on the rail, said means consisting of a spring-latch 18 rigidly secured to the upper side and projecting rearwardly of hanger 12. A groove 19 in the under face of latch 18 engages the upper end of dog 7, thus insuring movement of the dog in either direction.

The lower end of the gate is secured in place against the load when in use by means of duplicate clutch or grip devices located on the outer face of the gate at the lower-most corners thereof, said devices being adapted to coöperate for this purpose with angle irons or rails 20 extending along and suitably secured to each side of the car, as will be hereinafter explained. Each of said clutch or grip devices comprises a hinge member 21, see Fig. 9, having one half thereof suitably attached to a beveled portion 22 on the face of lower cross member 2 of the gate. The outer or free half of member 21 projects beyond the side of the gate, and is provided near its outer end with a hole 23 adapted to receive a grip rod 24. Said rod 24 is bent at one end to form a hook portion 25 adapted to engage with a series of holes 26 in the upper face of rail 20, and is provided at its opposite end with an eye portion 28 which serves to prevent hinge 21 from accidentally slipping off the grip rod at that end. The free end of hinge member 21 is of such length that when grip rod 24 engages with one of the holes 26 in angle iron 20, rod 24 is maintained at a slight angle to the longitudinal axis of the car. Thus, it will be seen that by reason of the angle at which rod 24 stands, and the slightly bent position of hinge member 21, due to said hinge member being mounted on beveled face 22, any movement of the lower end of the gate away from the load will immediately cause the free end of hinge 21 to tightly grip or bind upon rod 24. This gripping or binding action is facilitated and quickened by reason of hinge member 21 being mounted on beveled face 22, as will readily be understood.

Although not essential to the operation of the device, the gate is shown in the drawings as provided with a hinged joint substantially midway of its height, the upper and lower sections of members 1 of the gate, on which the joint is formed, being connected by means of hinges 28 secured to the inner faces thereof. The particular purpose of this joint is to allow the gate to be "broken," in order to more readily position it relative to the load, should the latter be unusually high and extend close to the center of the car.

Locking means are provided on the outer

face of each gate member 1 opposite hinge 28, for maintaining the gate in its normally rigid form. A buckle 29, pivotally secured in the lower end of member 30, which is 5 suitably secured to the upper section of member 1, serves to engage with hook portion 31 of member 32, attached to the lower section of member 1, thus maintaining the lower section of the gate in line with the 10 upper section. Sufficient space is allowed between the abutting ends of the upper and lower gate sections to permit buckles 29 to be readily slipped over hooks 31. Button 33, pivotally secured to the face of member 15 1, co-acts with hook portion 31 of member 32 to prevent buckle 29 from disengaging from said hook portion, as when the gate is swung into its horizontal position.

On the under face of lower member 2 of 20 the gate, and directly beneath members 1, there are provided hook members 34, pivotally attached to member 2 and adapted to serve as a means for supporting the lower end of the gate from tracks 4 in the horizontal position in which it is stored when 25 not in use. Hooks 34 are attached to member 2, as shown in Fig. 6, so as to allow a greater portion of the hook member to project below the pivot than above, whereby 30 the lower end of the hook member is rendered heavier than the upper and the hook is always kept in a substantially upright position, whereby to readily engage with tracks 4 without manual adjustment. Maintenance of this position is further insured 35 by the location of the pivotal point nearest the notched side of the hook member 34 as shown. The upper beveled edge of the hook members also facilitate their engagement with said rails. The upper end of the 40 gate is supported in this position by means of hooks 16 and hanger pins 15, as hereinbefore explained.

A hook 35 is secured to the car ceiling directly above each supporting rod 4 about midway the length of the car, said hook being adapted to engage its corresponding rod and prevent sagging and springing thereof when the bracing gate is hung 50 thereon.

In the operation of the device, the same being illustrated as applied to a load of fruit crates, merely by way of illustration, said crates are loaded in the car and arranged in the usual manner shown in Figs. 1 and 2, the device itself being stored in its horizontal position adjacent the car ceiling so as not to interfere with the loading operation. The car having been loaded, 55 hooks 34 are disengaged from rails 4 and hooks 16 from pins 15, and the gate lowered and positioned firmly against the face of the load. The hooked ends of rods 24 of the lower securing means are then placed in

the proper holes 26 in angle irons or rails 65 20, and the free halves of hinge members 21 pushed up as far as possible on rods 24, said members 21 serving, upon release, to firmly and positively clutch or grip rods 24, as hereinbefore explained. 70

To secure the upper end of the gate, chain sections 10 are first drawn taut by moving hanger 12 together with dog 6 toward the load. Take-up dogs 7 are then placed such distances from main dogs 6 as will be necessary to place springs 8 under a tension proportionate to the weight of the load carried. Take-up springs 8, having been placed under tension by moving dogs 7 away from the gate, will cause each of said dogs to assume 80 a rigid and positive grip upon its supporting rail 4 due to the leverage which the recoil of the springs exert upon dogs 7. 75

Thus, it may readily be seen that any slack occurring in the load incident to sudden movement or jerking of the car, will be quickly and positively taken up through the gate by virtue of its being connected at its upper end with dogs 6 which in turn are continually drawn toward dogs 7 by 90 means of the tensioned springs connecting the same. 85

Due to the continuous action of the automatic take-up devices at the upper end of the gate, said gate will exert a leverage action against the face of the load with the upper part thereof acting as a fulcrum, thereby tending to force the lower end of the gate outward. Any outward movement of the lower end of the gate will only serve to 100 increase the gripping or binding action of hinge members 21 on grip rods 24, as hereinbefore explained, thus precluding any tendency of the gate to work loose at the lower end. 105

A similar load-bracing gate with its corresponding securing means are provided to brace the load in the other end of the car. This latter gate may be lowered from its horizontal position adjacent the car ceiling 110 and allowed to rest temporarily against the gate securing the braced load, in order to allow loading of the remainder of the cargo and the bracing thereof in the manner hereinbefore explained. 115

In order to remove the gate from its operative position against the load, spring dogs 7 are first loosened and slid forward on rails 4 toward the gate, thereby permitting main dogs 6 to be moved forward 120 until the upper end of the gate is free from the load. The lower end of the gate may then be released by lifting the hooked ends 25 of pins 24 out of engagement with the holes 26 in angle irons 20, the binding action of hinge members 21 on grip pins 24 having been relieved upon the releasing of the upper securing means. On the other 125

hand, the lower securing means may be released first by forcing the lower end of the gate firmly against the load, thus relieving the binding action of hinge members 21 on grip pins 24, whereby the latter may be removed from engagement with holes 26. The upper securing means may then be released, as above explained.

During transit, when the load is 10 pressed, due to jar or impact, the gate will follow it up, dogs 6 being drawn to a greater or less extent toward dogs 7 by movement of springs 8, thus maintaining the gate in constant binding contact with the load. In 15 case the load should fail to resume its normal proportions after impact, the gate will still securely brace the same, due to the continual compensating action of take-up springs 8. Should the load tend to expand 20 dogs 6 will be swung forward at their lower ends by reason of their connections with the gate, thereby causing said dogs to clamp or bind on supporting rails 4 and consequently prevent outward movement of the 25 gate.

The device, constructed as hereinbefore described and explained, does not require the use of extraneous means, such as tools, nails, etc., in order to operate the same, and may 30 be readily manipulated by one person with no trouble whatever.

What I desire to claim is:—

1. A device of the character described, comprising the combination with a car, of 35 a load-bracing member adapted to be swung into and out of a substantially vertical position; means for securing the lower end of said bracing member to the lower portion of the car; tracks located in the upper portion of the car; automatic take-up means interposed between the upper end of the bracing member and the tracks, and adapted 40 to maintain said bracing member in constant binding relation to the load; and 45 means, movably mounted on said tracks, from which the load-bracing member may be suspended independent of said take-up means.

2. A device of the character described, 50 comprising the combination with a car, of a load-bracing member adapted to be swung into and out of a substantially vertical position; means for pivotally securing the lower end of said bracing member to the lower portion of the car; tracks located in the upper portion of the car; automatic take-up 55 means interposed between the upper end of the bracing member and the tracks, and adapted to maintain said bracing member in constant binding relation to the load; hangers, 60 movably mounted on said tracks, from which the load-bracing member may be suspended independent of the take-up means; and means for causing said take-up means 65 to move freely on said tracks in unison with

said hangers, when the bracing member is suspended from the latter.

3. A device of the character described, comprising the combination with a car, of a load-bracing member adapted to be swung 70 into and out of a substantially vertical position; means for pivotally securing the lower end of said bracing member to the lower portion of the car; tracks located in the upper portion of the car; suspension and 75 clutch means connected to the upper end of the bracing member and movably mounted on said tracks; corresponding clutch members adjustably mounted on the tracks and adapted to engage therewith; elastic tension means connecting the last named clutch members with the corresponding suspension and clutch means and adapted through the latter to draw said bracing member against the load; hangers, movably mounted 80 on said tracks, from which the bracing member may be suspended independent of said supporting and clutch means; means provided on said hangers and adapted to cause said supporting and clutch means and 85 said clutch members to move freely on said tracks in unison with said hangers, when the bracing member is suspended from the latter.

4. A device of the character described, 95 comprising the combination with a car, of a load-bracing member adapted to be swung into and out of a substantially vertical position, said bracing member being hinged transversely substantially midway of its 100 height; locking means for securing said bracing member in rigid form; means for pivotally securing the lower end of said bracing member to the lower portion of the car; tracks located in the upper portion of 105 the car; and automatic take-up means interposed between the upper end of the bracing member and the tracks, and adapted to maintain said bracing member in constant binding relation to the load. 110

5. In a device of the character described, the combination of a car; tracks located in the upper portion thereof; a load-bracing member; automatic clutch mechanism for securing the lower end of said bracing member to the lower portion of the car; and adjustable tension mechanism interposed 115 between said tracks and the upper end of the load-bracing member and serving to draw the upper portion of said member against 120 the load.

6. In a device of the character described, the combination of a car; tracks located in the upper portion thereof; a load-bracing member; clutch mechanism for securing the 125 lower end of said bracing member to the lower portion of the car; and adjustable tension mechanism interposed between said tracks and the upper end of the load-bracing member and serving to draw the upper por- 130

tion of said member against the load, thereby actuating the clutch mechanism securing the lower end of said bracing member.

7. In a device of the character described, 5 the combination of a car; tracks located in the upper portion thereof; a load-bracing member; clutch members provided on the lower end of said bracing member; rails located in the lower portion of the car; grip rods, slidably mounted in the ends of said clutch members, and with which said clutch members are adapted to engage; means for adjustably connecting the inner ends of said grip rods and said rails; and adjustable tension mechanism interposed between said tracks and the upper end of the load-bracing member and serving to draw the upper end of said member against the load.

8. In a load binder, the combination of a 20 car; tracks located in the upper portion thereof; a load-bracing member; clutch members secured to the lower end of said bracing member; rails located in the lower portion of the car; means interposed between said rails and the clutch members, with which the clutch members are adapted to engage; elastic tension mechanism interposed between the upper end of said load-bracing member and said tracks and serving to maintain said bracing member in 25 constant binding relation to the load.

9. A device of the character described, comprising the combination with a car, of tracks located in the upper portion thereof; 30 a load-bracing member; spring tension means interposed between the upper end of said bracing member and the tracks and serving to maintain the bracing member in constant binding relation to the load; and 35 clutch mechanism for pivotally and adjust-

ably securing the lower end of said bracing member against the load.

10. In a device of the character described, the combination with a car, of tracks located in the upper portion thereof; a load-bracing member adapted to be positioned against the face of the load; rails located in the lower portion of the car; clutch mechanism interposed between said rails and the lower end of said bracing member for securing 45 said end in place, said clutch mechanism being adapted to be actuated upon outward movement of the lower end of the bracing member; tracks located in the upper portion of the car; and spring tension means 50 interposed between the upper end of the load-bracing member and said tracks and serving to maintain the upper end of said bracing member in constant binding relation to the load.

11. A device of the character described, comprising the combination with a car, of a load-bracing member adapted to be swung into and out of a substantially vertical position, said bracing member consisting of a 55 plurality of sections transversely hinged together; locking means for securing said bracing member in rigid form; means for pivotally securing the lower end of said bracing member to the lower portion of the 60 car; tracks located in the upper portion of the car; and automatic take-up means interposed between the upper end of the bracing member and the tracks, and adapted to maintain said bracing member in constant 65 binding relation to the load.

In testimony whereof I have signed my name to this specification.

BENJAMIN S. GALLUP.
